UNITED STATES PATENT OFFICE.

FREDRICK BEIERMEISTER, JR., OF TROY, NEW YORK.

COLLAR.

SPECIFICATION forming part of Letters Patent No. 278,677, dated June 5, 1883.

Application filed September 9, 1882. (No model.)

To all whom it may concern:

Be it known that I, FREDRICK BEIERMEISTER, Jr., of the city of Troy, county of Rensselaer, and State of New York, have invented 5 a new and useful Improvement in Collars, which improvement is fully set forth in the following specification and accompanying drawings, in which—

Figure 1 is a perspective view of a finished 10 collar. Fig. 2 is a cross-section, exaggerated in size, of said collar, taken at the dotted line *a* *b* in Fig. 1. Fig. 3 is a perspective of an un- 15 finished collar. Fig. 4 is a cross-section taken at the dotted line *x* *y* in Fig. 3, exaggerated in size.

Similar letters of reference indicate corresponding parts in the several figures.

My invention consists in fastening or stitching together the outer and inner parts of a combined standing and turn-down collar along the dividing-line between the standing and turn-down portions of the collar, and is supplemental to my invention of a collar for which Letters Patent were granted to me June 13, 25 1882.

The objects of my invention are, first, to secure a firm and uniform condition of the upper or standing part of the collar; and, second, to confine the spring of the parts to the 30 lower or turn-down portion of the collar and keep the parts in their proper relative position while being laundered.

For convenience of description, the two parts of the collar may be styled one the "inner" part, 35 *D*, which answers the purposes of a band, and the other the "outer" part, *B*, which is the face of the collar. The outer part or face, *B*, is divided by the line of stitching *A* through parts *B* and *D* into two parts, known as the "upper" 40 or "standing" part and the "lower" or "turn-down" part. The outer part, *B*, may be composed of two or more plies or thicknesses of cloth, *FG*, Fig. 4. These plies are first stitched together along one edge of each ply, and then 45 turned to the position shown in Fig. 4. One or more plies, *D*, are then laid upon one side of part *B* and one or more plies upon the other side. The plies are then all stitched together at *E*, and those on one side—*D*, for example— 50 are turned over to the other side—and to the

position shown in Fig. 2, the stitching *E* being also turned over, so as to present on one side the smooth face *B*. It is preferable to then stitch all the plies to place, as shown by the line *H* in Fig. 2. We now have the two parts *D* and *B* in position shown in Fig. 2 to be stitched together at *A*. The utility of the stitching will be better understood by reference to Fig. 3, wherein the shape of the different parts is shown in perspective, and in that stage of progress represented by the cross-section in Fig. 4. It will be seen that the inner part, *D*, projects at each end beyond the outer part, *B*, which is partly represented by dotted lines; and that both parts are of the same shape along 60 their upper edges and part way only across their ends, and that their upper edges are curved. It is evident that the arc of a circle formed by these upper curved edges is longer than a corresponding arc taken a little below 65 their edges, so that when the parts are turned from the position shown in Fig. 4 to the position shown in Fig. 2 the edges forming the longer arc are brought down to contact with the part *B* at a shorter arc, at or near the line *H*, and being already stitched together at their 70 edges, and again at *H*, two arcs having different radii are connected into one arc, which causes the parts to assume a new line of curvature, and tends to separate their opposite edges 75 and prevent them from lying closely and smoothly together. This feature is well known and understood by those skilled in the art of making collars, and may be called the "spring" of the collar, the amount of spring varying 80 with the degree of curvature.

As I desire to secure the advantages of a standing collar in the upper portion of my collar, I wish to have the same firm and compact, and therefore stitch the parts together along 90 the line *A*, which holds the upper portion of the two parts firmly together and causes them to assume a smooth and uniform condition when laundered. By means of the same line of stitching, *A*, I also retain the spring of the 95 collar in the lower or turn-down portion, which permits the easy insertion of a necktie thereunder and between the two parts *B* and *D*. The stitching *A* also holds the parts securely in position while being laundered, which gives 100

them a uniform appearance when finished for use. The respective parts may be stitched around their edges, as indicated by the dotted lines in the drawings.

5 What I claim as new, and desire to secure by Letters Patent, is—

A collar composed of two parts curved and stitched together along the upper edge of each part, and again stitched together along the body of the parts, between their stitched and loose edges, whereby the upper portions of

said parts, above the body-line of stitching, are held firmly together, and the lower portions, below the body-line of stitching, left loose and allowed to separate from each other, substantially as described, and for the purposes set forth. 15
